UNITED STATES PATENT OFFICE.

ARTHUR W. A. BARTLETT AND ROBERT M. KERR, OF DETROIT, MICHIGAN, ASSIGNEES
TO DETROIT DENTAL MANUFACTURING COMPANY, OF DETROIT, MICHIGAN, A
CORPORATION OF MICHIGAN.

BLOWPIPE.

1,106,914.

Specification of Letters Patent. Patented Aug. 11, 1914.

Application filed March 16, 1912. Serial No. 684,196.

To all whom it may concern:

Be it known that we, ARTHUR W. A. BARTLETT, a subject of the King of Great Britain and Ireland, and ROBERT M. KERR, a citizen 5 of the United States of America, residing at Detroit, in the county of Wayne and State of Michigan, have invented certain new and useful Improvements in Blowpipes, of which the following is a specification, reference being had therein to the accompanying drawings.

10 The invention relates to Bunsen burner blow pipes and is more particularly designed for use in dentistry.

15 It is the object of the invention to obtain a construction in which the burner may be adjusted to any desired angle for directing the flame upon the work and the flame may be controlled without disturbing the position 20 of the burner.

To this end the invention consists in the construction as hereinafter set forth.

In the drawings,—Figure 1 is a perspective view of the blow pipe; Fig. 2 is a fragmentary, vertical, central cross section; Fig. 3 is a similar view showing a modified construction; Fig. 4 is a longitudinal section through the burner.

25 A is the base plate preferably of circular form and upon which the blow pipe is mounted, B is a tubular frame having a pivotal connection with the base which is formed by a round cross bar C engaging a transversely apertured post D having a 30 threaded shank E engaging a correspondingly threaded aperture in the base. This construction permits of adjusting the tubular frame B at any desired angle to the base and in then clamping it in this position by screwing down the post D which binds the cross bar C upon a boss F on the base surrounding the post.

35 The tubular frame B is formed of two parallel tubes or conduits arranged upon opposite sides of the post D and constituting respectively the air and gas supply conduits to the burner. These parallel conduits G and G' are joined to the cross bar C, which latter constitutes a continuation of one of 40 the conduits, and a nipple for attaching the flexible hose thereto. As shown in Figs. 1 and 2, the air conduit is attached to the nipple H formed on the cross bar C and the conduit extends through said cross bar to 45 the tube G on the opposite side thereof.

The gas conduit is connected to a nipple I secured to the tube G', being arranged in close proximity to the nipple H. In the modified construction shown in Fig. 3 the nipples are formed upon opposite ends of 50 the cross bar C in alignment with each other. Both constructions permit of adjusting the angle of the tubular frame B without any stress upon the flexible tubes connected thereto and furthermore, the tension of these 55 tubes upon the nipples on account of their proximity to the axis of the pivot will have little tendency to disturb the adjustment in the angle of the tubular frame.

60 The burner J is pivotally mounted at the upper end of the tubular frame B and consists of a cylindrical air and gas mixing chamber centrally apertured at its outer end. Within this chamber is the air blast nozzle K which is connected with the air conduit G through the trunnion connection between 65 said conduit and the burner. In like manner the gas conduit G' is connected through the opposite trunnion with the burner and communicates with the mixing chamber surrounding the nozzle K. The trunnions L and L' which form the mechanical connection between the tubular frame and burner form a ground joint with the latter, which is gas and air tight, and these trunnions also constitute valve casings for controlling valves M and M' respectively for the air and gas. The valves M and M' are preferably needle 70 valves and are adjusted by thumb wheels O and O' in proximity to the trunnions, in 75 which position they may be easily adjusted by the operator without disturbing the angle of adjustment either of the tubular frame or of the burner J which is independently 80 adjustable on the trunnions L, L'. 85

85 With the construction as described in use, the operator may adjust the tubular frame B to the required angle and the burner J may be independently adjusted to properly direct the flame. The frame B is held 90 rigid by clamping the same to the base through the rotative adjustment of the post D. The burner J is held in its position of adjustment by the friction of the trunnions L and L' which are resiliently pressed 95 against their seats in the burner by the tubes G and G'. Inasmuch as the valves M and M' engage the trunnions and not the burner, the adjustment of these valves will not disturb the angle of adjustment of the burner 100 105 110

but the flame may be regulated as desired. For convenience in manufacture the outer case of the burner is formed with a detachable cap portion P' which when removed will expose the nozzle J and permit of assembling the parts.

What we claim as our invention is:

1. In a blow pipe, the combination with a base, of a tubular frame, a burner carried by said tubular frame, a cross bar on said frame, and a post forming a bearing for said cross bar adjustably engaging said base and constituting a clamp for holding said tubular frame in different positions of angular adjustment.
2. In a blow pipe, the combination with a base, of a tubular frame comprising spaced air and gas conduits, a cross bar, a post carried by said base to which said cross bar is pivotally connected, a burner carried by said tubular frame, said cross bar constituting an extension of one of said conduits, and said post being adjustable in relation to the base to constitute a clamp for holding said tubular frame in different positions of angular adjustment.
3. In a blow pipe, the combination with a base, of a frame comprising parallel air and gas tubes, flexible conduit engaging nipples upon said tubes, said frame having a cross portion pivotally connecting the frame with said base, a burner between said tubes at the upper end thereof, hollow members connect-

ing said burner with said tubes, and controlling valves within said hollow members 85 having their operating stems in axial alignment therewith.

4. In a blow pipe, the combination with a frame comprising spaced air and gas conduits, of a burner at the upper end of said frame arranged between the conduits, hollow angle-shaped members carried by said conduits having bearing faces, co-operating bearing faces on the burner, and valves within said hollow members having their operating stems in axial alignment therewith, said burner being held in its position of adjustment by the friction of said hollow members, which are constructed to be resiliently pressed against the bearing surfaces on the burner by the spaced conduits.

5. In a blow pipe, the combination with a frame comprising spaced air and gas conduits, of a burner at the upper end of said frame arranged between the conduits, hollow members connecting said burner with said conduits, and controlling valves within said hollow members.

In testimony whereof we affix our signatures in presence of two witnesses.

ARTHUR W. A. BARTLETT.

ROBERT M. KERR.
